WINDMILL

Charles H. Wigzell, Big Lake, Tex., assignor of two-eighths to J. C. Wigzell, one-eighth to Ralph Wigzell, and one-eighth to Alden Wigzell, all of Big Lake, Tex.

Application August 19, 1937, Serial No. 159,961

3 Claims. (Cl. 170—47)

This invention relates to new and useful improvements in windmill structures, and control mechanism therefor.

The principal object of the present invention 5 is to provide a windmill structure wherein the tail can be readily controlled from the bottom of the windmill.

Another important object of the invention is 10 to provide a windmill in which the vanes assembly is constructed in such a manner that repair and replacements can be performed conveniently and at low cost.

These and various other important objects and 15 advantages of the invention will become apparent to the reader of the following specification.

In the drawings:

Figure 1 represents a side elevational view of 20 the upper portion of the windmill with parts broken away.

Figure 2 is an enlarged vertical sectional view 25 through the head structure of the windmill.

Figure 3 is a section taken approximately on line 3—3 of Figure 2 with parts removed.

Figure 4 is a fragmentary vertical sectional 30 view showing the rod plunger.

Figure 5 is a fragmentary sectional view 35 through the rod plunger.

Figure 6 is a side elevational view of the shaft 40 of the vanes assembly.

Figure 7 is a side elevational view of one of 45 the planetary gears.

Figure 8 is an inside elevational view of the 50 back plate of the windmill head.

Figure 9 is a fragmentary longitudinal sectional view through the packing gland.

Figure 10 is a fragmentary sectional view 55 of the tensioning means for the tail.

Figure 11 is a section taken substantially on line 11—11 of Figure 10.

Figure 12 is a top plan view of the disc shown 60 in Figure 10.

Figure 13 is a fragmentary sectional view taken substantially on line 13—13 of Figure 1.

Figure 14 is an elevational view of the brake 65 shoe.

Figure 15 is a fragmentary front elevational view of the vanes assembly.

Figure 16 is an elevational view of one vane 70 unit.

Referring to the drawings, wherein like numerals designate like parts, it can be seen that 75 numeral 5 represents a shell structure forming part of the head of the windmill, and from this depends the barrel 6 into which threads the tube 7. The lower end of the tube 7 has the packing gland 8 therein to prevent the escape of lubricant from the gear case. The tube 7 slidably receives the plunger 9, this plunger being provided with packing rings 10 and a pocket 11 80 in the upper end thereof for receiving the lower

end of the rod 12. The rod 12 is pivotally connected to the plunger 9 by a pin 13 passing through the plunger and lower end of the rod 12.

A bore in the plunger 9 snugly receives the lower rod section 14 and a pin 15 serves to fix 5 the rod 14 to the plunger 9.

The lower rod section 14 extends downwardly through the packing gland 8 and connects as at 16 to the utility means 17.

More specifically, the packing gland 8 consists 10 of a valve 18 threadedly disposed into the lower end of the tube 7 and into each end of this barrel 18 a bushing 19 is threadedly disposed. In the barrel 18 intermediate its ends is a ball bearing assembly consisting of the race plates 19—20 15 with the ball bearings 21 interposed between the same.

Packing units are also located in the barrel 18 one bearing against the inner end of each bushing 19 and each of these packing units consists 20 of a pair of plates 22—22 provided with circumferentially disposed ribs on the inner side thereof, while interposed between these plates is a body of felt 23.

Interposed between each of the innermost discs 25 22 and the corresponding ball bearing race plates 19—20 is a coiled compressible spring 24. Obviously, any taking up or letting out of one spring 24 can be performed without affecting the nut 19 of the other spring, through the use of the 30 aforementioned ball bearing assembly. Furthermore, the tensioning of the packing units expands the felt mounting 23 to snugly engage the inner side of the barrel 18 and also the rod 14.

The upper end of the rod 12 is threadedly disposed into the collar 25 and this collar is recessed to accommodate ball bearings 26 which ride on the shank portion 27 of the gear 28. This gear 28 represents one of the planetary gears 28—29 and 30, which mesh with the sun gear formation 40 31 on the inner end of the air shaft 32.

It can also be seen that the inside of the head structure 5 is formed to provide the ring gear 33 with which the planetary gears 28—29 and 30 mesh. Furthermore, as shown in Figure 2, an 45 annulus 34 divided into a pair of semi-circular sections is bolted in place as at 35 so as to overlap the planetary gears and to prevent displacement of the same in relation with the ring gear 33.

It can also be seen that the head structure 50 5 is provided with a removable back plate 36 which, as shown in Figure 8, is provided with a gear formation 37 with which the pinion formation 38 on the shank 27 of the planetary gear 55 28 meshes, and it will be observed that the shank 27 is provided with a small pintle 39 which rides against the shoulder 40 of the said plate 36. The plate 36 is held to the head by bolts or screws 41. A closure plate 42 is provided for the 60

top of the head and this can be removed to permit access to the interior of the head.

As shown in Figure 6, the shaft 32 is provided with a polygonal portion 43 at an intermediate point and a polygonal portion 44 at its outer end portion which merges with the threaded portion 45 and also with the threaded portion 46.

Figure 16 shows one of the vane units which consists of a hub 47 provided with the square opening 48 therein and the blades 49—49 radiating therefrom.

These blade units can be stamped from sheet metal, the outer units being arranged on the squared head portion 44 of the shaft 32, while the inner units are arranged on the squared portion 43 of the shaft. The hubs 47 of the inner group are banked against the shoulder 50 of the shaft by jam nuts 51 on the threaded portion 46, while the hubs of the outer group are banked against the shoulder 52 by a nut 53 on the threaded portion 45.

The blades of the inner and outer groups are brought into interlapping relation as suggested in Figure 1 and held in this manner by tie rods or wires 54 trained through openings 55 in the blades. These tie rods or wires can have turnbuckles 56 therein.

To turn the tail structure 58, a handle 59 is provided on the tail frame and from this extends the chain 60 passing over the pulley 61 to connect as at 62 to the eye 63 of the inverted V-shaped connector 64 which extends through guide 65 on the head 5. This frame 64 has its lower end disposed through an annulus 66 and provided with nuts 67. The annulus 66 engages under the annulus 68 which is provided with a depending annular flange 69 overlapping the annulus 66 and extending downwardly from the flange 69 is the bail-like structure 70 which connects at its lower end to the control line 71.

Obviously, by pulling on this control line, setting of the tail can be accomplished.

The brake mechanism consists of the vertical shaft 72 extending between the arms 73—74 of the head structure 5. The lower end is squared as at 75 to seat in a square socket in the arm 74. A lower frame bar 76 of the tail 58 is swingable on the lower portion of the shaft 72, while the upper bar 77 of the frame is swingable on the upper portion of the shaft 72 and has the arm 78 passing under the arm 73 and extending upwardly to be connected by the rod 79 to the rocker 80 on the front portion of the head 5. This rocker 80 is provided with the foot portion 81 which bears against the rocker arm 82 and which at its lower end carries the pivotal brake shoe 83 operative against the smooth portion a of the shaft 32.

Located on the shaft 72 are the pair of freely rotatable gears 84 between which is located the disc 85. The disc 85 is keyed as at 86 to the shaft 72 and has a pair of ears 88 projecting laterally therefrom abridged by the pin 89. The pin 89 defines an opening 90 through which the shaft 91 is disposed and this carries the pair of pinions 92 which mesh with the gears 84. The upper end of the shaft 91 is bifurcated to pivotally receive the crank handle 93.

Obviously, when the gears 84 are thus rotated, tensioning or untensioning of the upper and lower springs 94—95, respectively, will result. The springs 94—95 are connected to the upper and lower gears 84—84 and also to the upper and lower frame bars 77—76 of the tail 58. To

prevent self adjusting of the tensioning means, the lugs 88 extend sufficiently far out from the disc 85 to permit the crank handle 93 to be dropped in between the same.

While the foregoing specification sets forth the invention in specific terms, it is to be understood that numerous changes in the shape, size, and materials may be resorted to without departing from the spirit and scope of the invention as claimed hereinafter.

Having described the invention, what is claimed as new is:

1. A windmill construction comprising a wind operated vane, a rod structure operated by the vane, a vertical barrel, a packing gland in the barrel, a gear case mounted at the upper end of the barrel, said vane having a shaft extending into the case, said packing gland being adapted to prevent lubricant from escaping from the case and barrel, a sun gear carried by the inner end 20 of the vane shaft, a ring gear fastened to the inside of the gear case, planetary gears meshing with the ring gear and the sun gear, an annulus, a stub shaft extending from one of the planetary gears and into the annulus, said rod being connected to the annulus.

2. A windmill construction comprising a wind operated vane, a rod structure operated by the vane, a vertical barrel, a packing gland in the barrel, a gear case mounted at the upper end of the barrel, said vane having a shaft extending into the case, said packing gland being adapted to prevent lubricant from escaping from the case and barrel, a sun gear carried by the inner end 35 of the vane shaft, a ring gear fastened to the inside of the gear case, planetary gears meshing with the ring gear and the sun gear, an annulus, a stub shaft extending from one of the planetary gears and into the annulus, said rod being connected to the annulus, said case being provided with a removable back plate insertable into a portion of the gear case, said plate provided with an annular grooveway having its opposed walls formed with teeth, said stub shaft being provided with a pinion-like formation on 45 its free end for mesh with the teeth of the opposed walls of the groove.

3. A windmill construction comprising a wind operated vane, a rod structure operated by the vane, a vertical barrel, a packing gland in the 50 barrel, a gear case mounted at the upper end of the barrel, said vane having a shaft extending into the case, said packing gland being adapted to prevent lubricant from escaping from the case and barrel, a sun gear carried by the inner end 55 of the vane shaft, a ring gear fastened to the inside of the gear case, planetary gears meshing with the ring gear and the sun gear, an annulus, a stub shaft extending from one of the planetary gears and into the annulus, said rod being connected to the annulus, said case being provided with a removable back plate insertable into a portion of the gear case, said plate provided with an annular grooveway having its opposed walls formed with teeth, said stub shaft 65 being provided with a pinion-like formation on its free end or mesh with the teeth of the opposed walls of the groove, said plate provided with a shoulder portion inwardly of the said groove, said stub shaft provided with a reduced 70 cylindrical extension for riding engagement with the shoulder.

CHARLES H. WIGZELL.
